(57) **CLAIM**

I claim the ornamental design for a lock receiving element for a hasp type closure, as shown and described.

DESCRIPTION

FIG. 1 is a perspective view of a lock receiving element for a hasp type closure of my new design;

FIG. 2 is a second perspective view of the lock receiving element for a hasp type closure of FIG. 1;

FIG. 3 is a front elevational view of the lock receiving element for a hasp type closure of FIG. 1;

FIG. 4 is a top plan view of the lock receiving element for a hasp type closure of FIG. 1;

FIG. 5 is a bottom plan view of the lock receiving element for a hasp type closure of FIG. 1;

FIG. 6 is a left side elevational view of the lock receiving element for a hasp type closure of FIG. 1;

FIG. 7 is a right side elevational view of the lock receiving element for a hasp type closure of FIG. 1; and,

FIG. 8 is a rear elevational view of the lock receiving element for a hasp type closure of FIG. 1, the rear elevational view does not form any part of the claimed invention. The dashed lines in FIGS. 1-8 represent environment and are for illustrative purposes only and do not constitute part of the claimed design. The phantom lines in FIGS. 1-8 define the border between claimed and unclaimed matter. The rear view shown in FIG. 8 are not claimed.
